STRIP CONTAINER FOR COILED SPRINGS

Filed July 24, 1929

UNITED STATES PATENT OFFICE

HERNARD R. SCHNEIDER, OF LYNDHURST, NEW JERSEY, ASSIGNOR TO EBCO MACHINE CORPORATION, OF NEW YORK, N. Y., A CORPORATION OF NEW YORK

STRIP CONTAINER FOR COILED SPRINGS

Application filed July 24, 1929. Serial No. 380,688.

This invention relates to strip container for coiled springs.

An object of the invention is to provide a container or covering in strip form for enclosing and retaining metallic coiled springs, of muslin, cloth or other suitable fabric and the like, doubled along its length or woven or sewed or otherwise secured at one longitudinal edge to give two plies or layers, 10 which are secured together transverse to the direction of length of the strip at regular intervals to form pockets into which the springs are inserted and retained. The securing of the two plies or layers trans- 15 verse of the direction of length of the strip to form the pockets, is preferably had by weaving in the making of the strip material, or by sewing or the like, such transverse securing beginning at the doubled edge 20 and extending but partially for the transverse width toward the open edges of the plies or layers, that is to say, at the mouths of the respective pockets, thus providing for terminal portions at the free edges of the 25 plies or layers which are entirely unstitched at such open edges for the length of the strip.

As is set forth in the co-pending application Ser. No. 363,869, filed May 17, 1929, by Karl Kaiser and myself, relating to a machine for inserting and enclosing metallic coiled springs into the pockets of the strip covering, the free edges of the plies or layers at the termini of the transverse secures provide an unobstructed passage from 30 mouth to mouth of the successive pockets of the strip container, thus rendering possible the use of a machine devised by said Kaiser and myself having a suitable carrier for feeding coiled springs successively into the 35 respective pockets.

Upon lodgment of the springs in the pockets, the free edges of the strip are stitched or otherwise secured to one another to effectively enclose the springs individually in 40 the respective pockets.

The strip of contained coiled springs is employed in the manufacture of mattressing and upholstering, and the like.

Further features and objects of the invention will be more fully understood from the

following detail description of the accompanying drawings, in which

Fig. 1 is a detail top plan view of a container strip pursuant to my invention, in which helical springs are enclosed in the respective pockets;

Fig. 2 is a sectional elevation on line 2—2 of Fig. 1, the springs being displaced ninety degrees in the respective pockets;

Fig. 3 is a sectional elevation on line 3—3 of Fig. 2;

Fig. 4 is a detail top perspective view of a strip container prior to insertion of the springs;

Fig. 5 is a detail top plan view of the free terminal portion of a transverse weaving, on a greatly enlarged scale; and

Fig. 6 is a sectional elevation on line 6—6 of Fig. 5.

Referring to Figs. 4, 5 and 6, the strip 10 of muslin, cloth or other suitable fabric or the like is doubled-over upon itself, or sewed or woven to provide an upper ply or layer 12 and a lower ply or layer 13. The doubled-over or sewed or woven edge 11 may be in the form of closer weavings, re-inforced weaving or inter-selvaged portion, connecting the body portions of two strips, as is illustrated in the drawings, the inter-selvaged portion providing for enhanced strength of the material. Pockets for the respective springs are formed successively lengthwise of the strip by any suitable means such as the weavings 14, stitches or the like, each transverse securing extending from a location 15 to a location 16, the distance between the locations 15, 16, being less than the transverse dimension or width of the strip 10, thereby providing for the regions 17 between the location 16 and the free edges 18 of the upper and lower plies or layers 12, 13, which are unobstructed by such transverse securing, thereby providing for inter-mouth passages at said regions 17 communicating with the respective mouths of the successive pockets, 85

to afford an unobstructed passage for the carrier or other member for inserting the respective springs in the successive pockets.

Fig. 1 shows my strip container in which springs 19 are enclosed in the successive

pockets 20 upon delivering from our machine, the stitchings 21 being applied at the theretofore free edges of the plies or layers 12, 13, the stitchings being made by a sewing machine or by other mechanical or manual sewing operation, or by any other suitable fastening or like means.

Whereas there is described in our aforesaid application, a wholly automatic device for feeding coiled or helical springs to a carrier for receiving and inserting a coil in each pocket successively and withdrawing from each pocket upon insertion of the spring therein, and further including automatic means for holding the springs after insertion in compressed status to enable or facilitate the stitching or other securing at the open mouths at the free edges of the plies or layers, it will be understood that my invention is also applicable for use with a spring carrier member or the like which may be supplied with springs by manual operation, or the springs inserted in the respective parts manually by any suitable carrier or by wholly manual operation; the free and unobstructed inter-mouth passages enabling the transit from mouth to mouth to be effected without obstruction by any weavings, stitchings, and without requiring the free edges of the layers or plies to be opened up or maintained in opened position by mechanical devices or manual operation.

Usually, and as is illustrated in Fig. 1 of the drawings the dimension between successive transverse securities 14, 14, is less than the width of the strip container material, and the springs 19 are displaced manually or mechanically about an angular movement of ninety degrees within the respective pockets, to locate the axes of the springs 19 in the direction of greater dimension in the respective pockets.

Preferably, the muslin or other fabric is woven as a doubled-up strip and to have a doubled inter-selvaged portion at the edge 11, and the transverse securities 14 may be attained by weaving for the locations of the transverse securities for the dimension from the location 15 to the location 16, such weaving being illustrated as to one manner thereof by interweaving alternate weft threads 22 of the lower ply or layer 13, with the weft threads 23 and warp threads 24 of the upper ply or layer 12, the warp threads 25 of the lower ply or weave 13 extending intermediate such interwoven weavings and the alternate weft threads 26 of the lower ply or weave 13. However, any other procedure of weaving or sewing or folding over of a single woven material may be used.

Pursuant to my invention as above set forth, and as illustrated in the drawings, the transverse securities effect engagement of the upper and lower plies at the locations of the securities. Furthermore, the secure-

ments are arranged substantially parallel to one another and substantially at right angles to the direction of length of the plies. By such construction, the mouths of the respective pockets are disposed at one and the same lateral side of the plies, thereby facilitating the operations of insertion of the respective coil springs within the pockets and the stitching or other securing in closing the mouths of the pockets.

Whereas, I have described my invention by reference to specific forms thereof, it will be understood that many changes and modifications may be made without departing from the spirit of the invention.

I claim:—

1. A strip for containing springs, comprising two layers secured to one another at one longitudinal edge, and means securing said layers in substantial engagement with each other at intervals to provide pockets between the layers to receive springs, the securing means extending substantially parallel to one another and terminating a definite spacing from the free edges of the layers to provide a clearance from pocket to pocket.

2. A strip for containing springs, said strip being doubled lengthwise to bring opposite longitudinal edges into proximity and form two layers, the strip having substantially parallel means to secure the layers together in substantial engagement with one another at uniform intervals to form pockets with open mouths adjacent said edges, said means extending across the strip substantially at right angles to the direction of length of the strip and terminating short of said edges.

3. A strip for containing springs comprising two layers secured at one longitudinal edge, and means securing said layers in substantial engagement with one another at substantially uniform intervals to provide pockets between the layers to receive springs, said securing means extending substantially at right angles to said longitudinal edge and from said longitudinal edge continuously to a location spaced from the opposite longitudinal free edges of the layers to provide a clearance from pocket to pocket.

In testimony whereof I have signed this specification this 17th day of July, 1929.

BERNARD R. SCHNEIDER.
